(57) **CLAIM**

The ornamental design for an access control device, as shown and described.

DESCRIPTION

The file of this patent contains at least one drawing/photograph executed in color. Copies of this patent with color drawing(s)/photograph(s) will be provided by the Office upon request and payment of the necessary fee.

1. Access control device

Fig. 1.1 is a first view of the access control device according to our design, in an unlighted state;

Fig. 1.2 is another view thereof lighted in red; and

Fig. 1.3 is another view thereof lighted in green.

The design is used for access control; it shows green or red light for authentication purposes and is without light in passive state.
